UNITED STATES PATENT OFFICE.

FREDERICK B. PETTENGILL, OF ROSEDALE, KANSAS, ASSIGNOR OF ONE-HALF TO EDWARD NICHOLSON, OF SAME PLACE.

STEAM-VALVE GOVERNOR.

SPECIFICATION forming part of Letters Patent No. 404,796, dated June 4, 1889.

Application filed November 13, 1888. Serial No. 290,758. (No model.)

To all whom it may concern:

Be it known that I, FREDERICK B. PETTENGILL, a citizen of the United States, residing at Rosedale, in the county of Wyandotte, State of Kansas, have invented certain new and useful Improvements in Steam-Valve Governors; and I do hereby declare that the following is a full, clear, and exact description of the same, which will enable others skilled in the art to which it appertains to make and use the same, reference being had to the accompanying drawings, forming a part of this specification.

My invention has for its object to equalize the centrifugal speed of a governor and control automatically the speed of a driven shaft in such a manner that the amount of power required to rotate the shaft under varying resisting loads shall be regulated in proportion.

My invention further consists in the novel construction and combination of parts, which will be first fully described, and specifically pointed out in the claims.

In the drawings, Figure 1 is a view in perspective, the governor mounted upon the steam-valve chamber of an engine and connected with the driven shaft, and showing the expanding pulley and the oscillating levers connected with the fly-balls and the adjustable bearing for the levers. Fig. 2 is a vertical sectional view of the fixed and rotary sleeves inclosing the valve-operating rod, and also of the expanding pulley, showing the fly-balls and arms in alternate positions, and one of the arms of the balls broken away at its pivotal point, showing one of the bearings on the rotating sleeve of said arm. Fig. 3 is a detail end view of the pulley, supporting-plate, and pulley, showing the radial dovetail retaining-slot in the plate and the radial dovetail tongue upon the quadrants of the pulley.

Similar letters of reference indicate corresponding parts in all the figures.

In the construction of the governor as ordinarily applied to the engine a flat circular base-plate A is made the proper size to fit the upper circular flange b of a valve-chamber B, to which flange it is secured by the bolts a a, the upper end portion of said chamber only

being illustrated, which contains the ordinary steam-valve. Connected at one end with the valve-chamber B is shown a steam-pipe C, the opposite end leading to and being connected in the usual manner with a steam-generating boiler.

In a vertical relation and in the center of the plate A is made a perforation a', which receives the valve-operating rod, which is operated as hereinafter described. To the peripherical portion of the plate A is connected the lower end of an arm D, which extends in the form of a goose-neck a short distance radially from the plate A, thence in an upwardly-curved plane, and the opposite end d' bent in a horizontal position and extended to a point over plate A. A circular flat plate d², which is smaller in dimensions than the plate A, is attached at its periphery to the end portion d' of the arm D, and said plate d² arranged in a horizontal position over plate A, so as to preserve the center of said plate d² in a vertical line with the center of the circular plate A. Through the central portion of the plate d² is made in a vertical relation a perforation d³, which is of the proper size to receive the lower end of a fixed sleeve E. Said sleeve E is rigidly attached to the circular plate d² and extends in a vertical relation a suitable height to permit the rotation and support the fly-balls of the governor, the diameter of the opening e in said sleeve E being relatively the same as that of the perforation a' in the plate A. Over the fixed sleeve E is then fitted loosely a rotating sleeve F, the lower end portion f of which rests upon the upper side portion of the plate d², and the upper end of said sleeve F extends a corresponding distance in height to that of the sleeve E. Extending around the outer and upper end portion of the sleeve F is made a lateral flange f', which extends a short distance from said sleeve. Upon the upper side portion of the flange f' is secured rigidly the forked lugs or pivot-bearings f² f³ for the arms supporting the fly-balls, which bearings are placed directly opposite each other in the line drawn diametrically through the sleeve F, and which bearings are inclined at an angle to and in an outward direction from the

flange f' , and between each of the respective forked lugs $f^2 f^3$ are formed the slots $f^x f^x$, which are made in the direction of the diameter of sleeve F. Upon the flange f' is also 5 attached the forked lugs $f^4 f^5$, which are similar to the lugs $f^2 f^3$ and arranged upon said flange diametrically opposite each other in a like manner, and are placed in opposite relation to each other and each respective lug 10 placed at equal distances from the lugs $f^2 f^3$ on said flange f' . In the sleeve E is then fitted loosely the valve-operating rod G, one end of which extends through the perforation a' in the plate A into the valve-chamber B, 15 and is connected to the steam-valve in the ordinary manner. The upper end portion of the said rod G extends a short distance above the upper end portion of the fixed sleeve, or so far as is requisite for its operation. Upon 20 the extreme upper end portion of the rod G is attached rigidly a circular flat cap-plate g . A short distance below the cap-plate g is fitted rigidly to and around rod G the circular flat plate g' , which rests upon the upper end 25 portion of the sleeve E, and also fits within the annular rabbet f^6 , which is formed upon the upper end portion of the sleeve F, between the end of sleeve E and the flange f' .

To the respective lugs $f^2 f^3$ are attached the 30 ball-carrying arms H H', which consist of straight rods of the proper length, upon the respective lower end portions of which are the balls H² H³. The elevating ends of the arms H H' are attached rigidly to the upper 35 ends of said arms and consist of flat plates $h h$, which are narrow in width and bent at right angles to the said arms H H', and are placed in the slots f^x of the lugs $f^2 f^3$ flatwise and inclined at an angle in the direction of 40 the upper end of the sleeve E. A pivot h' is then inserted in a transverse relation through the lugs $f^2 f^3$, and also through the portions $h h$ of the arms H H'. From the pivotal point of connection of the portions $h h$ of the arms 45 H H', with the lugs $f^2 f^3$ in the direction of the rod G, is made the extensions or loops h^2 of said portion $h h$ of arms H H', which extend from the horizontal direction of the portion h of said lugs in the direction of the rod 50 G and contracted in width to fit loosely between the cap g and the circular plate g' a suitable distance to elevate the rod G.

For the purpose of regulating automatically 55 the action of the valve-operating rod G a circular flange or plate f^6 , of the relative proportions of the plate d^2 , is extended around the sleeve F and attached rigidly thereto a short distance above the plate d^2 . Extending around the sleeve F, and resting upon the 60 plate f^6 and attached rigidly to said sleeve, is a flat circular plate I, which is of the proper size to support the expanding pulley herein-after described.

Extending through the plate I and radially 65 to the sleeve F, from a point a short distance from said sleeve to the periphery of the plate I, are made a suitable number of wedge-formed

slots i , corresponding to the number of lugs on the flange f' on the sleeve F and intersecting with a vertical line extended through said 70 lugs and said plate I. An expanding pulley K is then made to extend around sleeve F, which is divided radially into separate parts or quadrants $k k k k$ and corresponding in number to that of the lugs on f' , or, as shown in the 75 drawings, to the lugs $f^2 f^3 f^4 f^5$. The respective upper and lower sides $k^2 k^3$ of the quadrants of the pulley are made smooth, and are placed horizontally upon the plate I. Upon the under side portion k^3 of each quadrant, at a 80 point equally distant from the dividing-line of each quadrant, is made a radial tongue k^4 , dovetailed inward from their upper edge, which extends through the radial slot i in the plate I, and fitted within said slot so as to 85 slide freely on the plate I in the direction of the sleeve F. In each quadrant of the pulley, in a vertical line with the tongues k^4 , is made a recess k^5 , which is slightly elongated radially to the sleeve F, and extends a portion of the 90 distance through said quadrant. A peripheral groove k^6 is then made around the pulley K and an equal depth in each quadrant. Around the sleeve F is fitted a vertically-adjustable loose collar L, and through said collar 95 is inserted an adjustable screw l, which impinges upon the sleeve F and secures the said collar adjustably in position. To the collar L is secured rigidly the forked lugs $l' l' l' l'$, which extend horizontally from the collar L and radially in relation to sleeve F, and are arranged in a vertical line with the lugs $f^2 f^3 f^4 f^5$. To the under side of the portion h of each one of the arms H H', and tangentially to the pivot h' , is attached a depending 100 lug h^3 , which extends from the said plate h relatively in position between the pivot h' and the lip h^2 . To operate the movable quadrants k of the pulley K, an equal number of flat bars or levers M are made of the required 105 length to extend from the lug h^3 on the respective portions h of the ball-carrying arms H H' to the quadrants k of the pulley and within the recess k^5 of said quadrants, which bars are first placed between the forked portions of lugs l' . The upper end portion m of each bar is then pivotally attached to the sides of said lug h^3 and the lower end portion pivoted with a knob m' , which decreases the 110 friction in the recess. 115

Through each of the bars M is made the longitudinal slot m^2 , which extends from a central point between the opposite ends of the said bar M a short distance to permit oscillation. In a transverse relation to and 120 through lug l , and extending through the slot m in the bars M, is inserted a pivot m^3 . Between the radial forked lugs l' , which are upon the collar L, beneath the lugs $f^4 f^5$, the bars M are similarly arranged, and for the purpose 125 of operating said bars M conjointly with the bars which are connected with the ball-carrying arms H H' a portion of the plate h is provided with the lip h^2 , and depending lug h^3 is 130

pivoted to and between the forked portions of the lugs $f^4 f^5$, and the said lip h^2 extended between the cap g on the rod G , so that when the rod G is elevated or depressed in the centrifugal movement of the fly-balls the said portions of the plates and lip connected with similar oscillating bars partake of the same movement as is given to the lips upon the ball-carrying arms. Upon the upper end side 5 of the base-plate A of the governor, near its outer edge in a line transversely related to the curved arm D , is attached a vibrating band-tightening arm N . One end n of said arm N is pivoted with forked end portions n' 10, which are perforated in one direction and receive a vertical pin n^2 , which pin extends within and is secured rigidly to plate A . Between the forked ends $n' n'$ of the arm N and around the pin n^2 is coiled a spiral spring n^3 , 15 one terminal end of which spring is secured to one of the lugs n' and the opposite terminal end extended in the line of direction of and against the side of the arm N . The opposite vibrating end n^5 of the arm N is bent 20 in an upwardly-curved direction in the horizontal plane of the pulley K , and upon said end is attached rigidly in a horizontal position a short cross-bar n^6 . Upon the opposite ends and upper side portion of the bar n^6 is 25 pivotally attached the horizontal grooved sheaves $n^7 n^8$. Around the driven shaft O is placed a grooved collar o , which is rigidly attached to said shaft. Around the pulley K on the governor N is then placed one end of 30 an endless band P , the opposite end of which band is carried outside of and over pulley n^7 on the belt-tightening arm N , and thence over the collar o on the shaft O , thence over the sheave n^8 on the belt-tightening arm N , and over the 35 portion of said sheave opposite sheave n^7 , and thence connected with the opposite end of the band on the pulley K . The arm N is then vibrated to a position parallel with shaft O , and the end of spring n^4 on the side of the 40 said arm preserves the belt constantly under tension.

In the operation of the governor the pulley and outer sleeve and attached fly-balls are driven from the shaft O and the balls fly out 45 from the center by centrifugal force. When the speed of the shaft O increases, the balls fly farther from the center, and so lower the valve-operating rod, and they reduce the opening of the regulating-valve, which is 50 connected with said rod. Steam being admitted to the steam-chamber B through the pipe C , the power imparted to the engine to drive shaft O communicates a rotary movement to the expanding-pulley K on the 55 governor. The position of the fly-balls $H H'$, as seen in Fig. 1, is normally at rest, and in this position the upper ends of the oscillating bars or levers M are carried in the direction of the sleeve F and the lower ends 60 projected outwardly, thus throwing the separate quadrants of the pulley widely apart and increasing the circumference of the pulley, 65

each segment being prevented from canting by means of the dovetailed tongue and groove. The position of the steam-valve in this position of the parts of the governor is such as to admit the full quantity of steam to the steam-valve chamber, as the speed of the shaft O , in the absence of any resistance caused by a load or work to be accomplished in its rotation, increases the speed proportionally and is communicated to the pulley K , and the balls $H H'$ fly from the center and widen their distance apart, and the movements of the bar M are such as to throw the lower ends toward 70 the sleeve F and draw the separate quadrants or sections of the pulley together, thus reducing the circumference of the pulley, the balls and valve-opening rod taking the position seen in Fig. 2, and thus closing the valve sufficiently in the valve-chamber B to decrease 75 the force of the steam, the size of the pulley, and the degree of rotation of shaft O to its normal speed.

The regulation of the governor is as follows: 80 The speed of the driven shaft O in the normal position of the governor at rest is such as to communicate a moderate centrifugal movement to the fly balls or weights, the pulley upon the governor is expanded to its full extent, and the degree of expansion is subject 85 to the oscillation of the connecting-bars and the rotation of the fly-balls. Consequently the steam admitted to the steam-valve chamber is when the balls are at rest unchecked. As 90 the speed of the shaft increases from its mean velocity the fly-balls describe a wider circle of rotation, the accelerated speed which the shaft has received is communicated to the pulley, which is accelerated in proportion to 95 its diminution circumferentially, and the fly-balls moved farther apart to a point in which the steam is cut off sufficiently to reduce the speed of the driven shaft to a mean velocity. Inversely the reduction of the speed of the 100 driven shaft from a mean velocity is communicated to the pulley upon the governor, and as the momentum of the shaft is reduced the fly-balls contract their circle of rotation, and the pulley expands proportionally and its 105 speed gradually reduced until the necessary increase of steam is permitted to meet the resistance of the shaft. When the shaft is loaded and the resistance of the driven shaft is occasioned thereby, the momentum of the 110 engine is slightly disturbed, the decreased revolutions of the shaft act directly upon the pulley and its speed reduced in proportion, the fly-balls take a contracted circle of rotation, and the expansion of the pulley follows, 115 which further reduces the speed in the same rate in which the resistance of the load decreases the momentum of the shaft. The fly-balls then take a still smaller circle of rotation and sufficient steam is admitted to increase 120 the rotation of the driven shaft to its mean velocity.

To vary the regulation of the governor so as to meet the necessary requirements in em-

gines of various degrees of power, the collar L is raised or lowered, as the case may be, which relatively lengthens or shortens the leverage of the oscillating bars M, and the dimensions of the periphery of the pulley are consequently increased or decreased normally and its regulation then effected automatically, as before.

Having fully described my invention, what I now claim as new, and desire to secure by Letters Patent, is—

1. In a centrifugal governor having fly-weights and a rotating sleeve, the combination, with said sleeve and weights, of a fixed plate, and an alternately expanding and contracting pulley having its sections movably keyed on said plate, and levers connected with said fly-weights and the sections of said pulley, substantially as described.
2. In a centrifugal governor having fly-weights, and alternately expanding and contracting pulley, and oscillating bars connected with said pulley and said weights, for the purpose described.
3. In a centrifugal governor having fly-weights and arms, the combination, with said arms, of a pulley consisting of movable sections, and oscillating bars connected with said arms and said sections and radially adjustable, as and for the purpose described.
4. In a centrifugal governor having a rotary sleeve and fly-arms on said sleeve adapted to support the fly-weights, the combination, with said arms and sleeve, of a pulley consisting of movable sections, oscillating bars connected with said arms and said sections, and an adjustable collar upon said

sleeve having lugs pivotally connected with said bars, for the purpose described.

5. In a centrifugal governor, the combination, with the rotating sleeve, of fly-weights, a radial supporting-plate, and a pulley having alternately expanding and contracting sections, and a recess in each section, radial lugs on said sleeve, and oscillating bars connected with said fly-weights and pivotally connected with said lugs, having an anti-friction end portion adapted to enter said recess in said section, for the purpose described.

6. In speed-regulating mechanism for engines, a governor having fly-weights, an alternately expanding and contracting pulley on said governor having movable sections, a driven-shaft, a power-conveying belt connected with the sections of said pulley and said shaft, and levers connected with the sections of said pulley and said fly-weights, for the purpose described.

7. In speed-regulating mechanism for engines, the combination of a governor having fly-weights, and an alternately expanding and contracting pulley having movable sections, levers connected with said sections and said fly-weights, a driven shaft, a power-conveying belt connected with the sections of said pulley and said shaft, and a self-acting belt-adjusting arm adapted to adjust the alignment of and tension of said belt, as described.

FREDERICK B. PETTENGILL.
